Inc., Chicago, Ill., a corporation of Illinois

Application March 7, 1944, Serial No. 525,431

7 Claims. (Cl. 250—13)

1

This invention relates to wave-signal translating systems and more particularly to two-way radio-communication systems of a type in which the field intensity of wave signals transmitted by a responding unit of the system in response to a signal from a distant source is controlled inversely in accordance with the field intensity of the wave signals received by that unit from the source.

In two-way radio-communication systems which heretofore have been employed, the field intensity of the signal transmitted by the responding unit of the system in response to a wave signal from the source has been independent of the field strength of the received signal at the responding unit. As a result of the transmission of signals of field strength unrelated to the field strength of the received signal, considerable unnecessary interference has been experienced in communication equipments, especially those operating in the ultra-high-frequency region and particularly when a number of transmitters are operating within a designated geographic area. It has been determined that this interference can be appreciably reduced and the frequency spectrum more efficiently utilized when signals are transmitted from responding units having field intensities varying in accordance with the received signal field intensity at the individual responding units. Specifically, it is desirable to control the field intensity of the signal emanating from a responding unit inversely in accordance with the field intensity of the signal received by that unit.

It is particularly useful to control the field intensities of signals transmitted by a responding unit in the manner just mentioned when relative movement exists between the two units of a two-way radio-communication system, since then the power output of one of the units can be regulated according to the varying intensity of received signals as influenced by the changing distance, geography, atmospheric conditions, or other factors existing between the two units. Additionally, power is expended only in accordance with the needs of altering situations, thus prolonging the life of equipment.

In addition to controlling the field intensity of a signal transmitted by a responding unit in accordance with the field intensity of a received signal at the unit, it is also expedient simultaneously to regulate the receiver sensitivity in the same manner. For the reception of signals having high field intensities, it is desirable to operate a receiver with reduced sensitivity or

2

especially for reception in the ultra-high-frequency region above 100 megacycles, to minimize the masking of the desired signal by receiver noise.

It is an object of the invention, therefore, to provide an improved wave-signal translating system which overcomes one or more of the above-mentioned disadvantages of the prior art systems.

It is a further object of the invention to provide in a two-way wave-signal communication system a responding unit which is effective inversely to regulate, in response to the field intensity of a received signal, the field intensity at the responding unit of a signal which is transmitted in reply to the received signal.

10 It is another object of the invention to provide a new and improved radio receiver-transmitter arrangement for a two-way communication system which not only regulates the sensitivity of its receiver but also controls the power output of its transmitter inversely in accordance with the field intensity of a radio signal received by the arrangement.

15 In accordance with the invention, a radio receiver-transmitter system comprises means at a point for receiving from a remote radio transmitting station during spaced receiving intervals radio signals having a field intensity at that point which may vary and for transmitting during intervals intervening the receiving intervals reply radio signals. The system also includes means responsive to the field intensity of a radio signal received during a receiving interval for deriving a control effect having a duration coextensive with the next succeeding interval 20 during which a reply radio signal is transmitted. The radio receiver-transmitter system further includes a control system responsive to the control effect for controlling the field intensity at the above-mentioned point of the reply radio signal, transmitted during the aforesaid next succeeding interval, inversely in accordance with the field intensity of the radio signal received during the above-mentioned receiving interval.

25 Also in accordance with the present invention, a wave-signal translating system comprises regenerative means at a point for receiving wave signals from a remote source and for transmitting related wave signals in reply thereto. The system also includes means responsive to the field intensity of received wave signals at that point for deriving a control effect, and a control system responsive to the control effect and including quench-oscillator means for controlling regeneration in the regenerative means during receiving 30 intervals to avoid saturation.

erative reception and for controlling the field intensity at the above-mentioned point of the related transmitted signals developed in the regenerative means during the transmission intervals inversely in accordance with the field intensity of the received signals at that point.

For a better understanding of the present invention, together with other and further objects thereof, reference is had to the following description taken in connection with the accompanying drawing, and its scope will be pointed out in the appended claims.

Fig. 1 of the drawing is a circuit diagram, partly schematic, of a complete wave-signal translating system embodying one form of the invention, while Fig. 2 comprises a block diagram of a modified wave-signal translating system in accordance with the invention.

Referring now more particularly to Fig. 1 of the drawing, there is illustrated a wave-signal translating system comprising means at a point for receiving wave signals from a source and transmitting related wave signals thereto. This means comprises a circuit 10 including a tube 11. The tube 11 is utilized in a combination super-regenerative receiving and transmitting system, normally referred to in the art as a transpondor. As used in this specification, the term "transpondor" is intended to describe a wave-signal translating system which includes a receiver and a transmitter so arranged that a predetermined answer or reply signal is transmitted in response to a received interrogating signal. The system is provided with an antenna 22 which is inductively coupled to an inductor 12 and connected to ground through an adjustable condenser 23. Tube 11 has included in its anode circuit a parallel-resonant circuit comprising the inductor 12, and a variable condenser 13. A grid-leak condenser combination comprising resistor 14 and condenser 15 is connected between one end of inductor 12 and the control electrode of the tube, while the cathode of the tube is grounded. The mid-point of inductor 12 is connected to ground through a radio-frequency choke 16 and the secondary winding of a step-up transformer 17. A diode rectifier 19 is connected between the anode of tube 11 and ground through a coupling condenser 18, the diode having a load resistor 20 connected across its electrodes through a choke winding 21.

The system of Fig. 1 also comprises means responsive to the field intensity of a received signal at the point of reception for deriving a control effect. This means comprises a control unit 60, the input circuit of which is connected across the diode load resistor 20, which unit will be more fully described hereinafter.

There is included in the wave-signal translating system of the instant invention a control system responsive to the control effect which is developed in control unit 60 for controlling the field intensity, at the point of reception, of the above-mentioned related transmitted signal inversely in accordance with the field intensity of the received signal. This means comprises a quench amplifier tube 41, a diode rectifier 50, and an amplifier 54. The input circuit of amplifier 41 is coupled to the output circuit of a conventional quench oscillator 40 through a coupling condenser 42 and to the output circuit of the control unit 60 by a resistor 43. The quench amplifier circuit is conventional and includes a tuned-anode circuit comprising an inductor 44 and a condenser 45 connected in parallel between the

anode and a source +B. The screen electrode of tube 41 is connected to a suitable source indicated +Sc. A cathode resistor 46 for tube 41 is bypassed to ground by a condenser 47.

The anode of amplifier tube 41 is inductively coupled, by a winding 48 tuned by a condenser 49, to the anode of the diode rectifier 50. The cathode of rectifier 50 is connected through a filter network comprising shunt condensers 51 and 52 and a choke winding 53 to the primary winding of the step-up transformer 17, which winding is also connected in circuit with the anode of amplifier 54. The cathode of this amplifier is grounded and suitable operating potentials are supplied to the screen and control electrodes from sources +B and -C, respectively, the latter being connected to the control electrode through a resistor 55. A blocking condenser 56 is connected between an intermediate point on winding 44 and the junction point between the choke 16 and the secondary winding of transformer 17.

There is also comprised in the arrangement of Fig. 1 a means responsive to the received wave signals for developing auxiliary signals. This means comprises an amplifier 57 which is connected between the output circuit of control unit 60 and a transmitter signal-developing system 58. The amplifier may be a conventional amplifier and the system 58 may comprise suitable means well known in the art, such as a multivibrator, which is responsive to each or to predetermined ones of applied input signals for developing the auxiliary signal. The system 58 is coupled to the input circuit of amplifier 54 through a coupling condenser 59.

Referring briefly to the operation of the system as a whole, but neglecting for the moment that of control unit 60 as it affects the remainder of the system, an alternating potential is applied to the tuned circuit 12, 13 of the superregenerative circuit including tube 11 by quench oscillator 40 through quench amplifier 41 to cause the regenerative circuit to fluctuate between an oscillating and nonoscillating condition at a rate corresponding to the operating frequency of the quench oscillator 40. Any signal which is intercepted by antenna 22 and applied to the tuned circuit 12, 13 causes oscillation of this circuit to begin sooner and to reach a higher amplitude than when no signal is being received. These oscillations of increased amplitude are applied to rectifier 19, wherein the modulation components are derived to develop across resistor 20 a pulsating unidirectional potential, for example, a signal having the wave form R, as when pulse-type signals having steep wave fronts are being received. The above-described operation is that of a conventional superregenerative receiver and detailed explanation is therefore deemed unnecessary.

The operation of the transmitter portion of the system will be described under the assumption that the derived modulation components of the received signal comprise the pulse R. The pulse R is impressed on the input circuit of control unit 60 and the signal which is derived therein, in a manner to be explained subsequently, is applied to the input circuit of amplifier 57 and is then translated to the transmitter signal-developing system 58, wherein an auxiliary signal comprising an output signal, such as the pulse T, having predetermined characteristics is developed and applied to amplifier 54. Units 57 and 58 are designed to respond to input signals which vary over a wide amplitude range. The anode potential for amplifier 54 is derived

by diode rectifier 50 from oscillations developed in the tuned circuit 44, 45 of quench amplifier 41 and in turn coupled to the tuned anode-cathode circuit of diode 50.

The pulse T applied to amplifier 54 from system 58 is amplified and further increased in amplitude by step-up transformer 17, the output of the latter being supplied to tuned circuit 12, 13 through radio-frequency choke 16. This signal supplies an increase in the anode potential to enable the oscillator circuit to function as a power oscillator. The signal also modulates the radio-frequency signal developed by the oscillator circuit 10 and there is transmitted from the antenna 22 a pulse-modulated carrier signal which is related to the received pulse R.

The above-described alternate reception of a wave signal from a source during spaced receiving intervals and transmission of a related wave signal thereto during intervals intervening the receiving intervals is, therefore, that of a conventional two-way communication system utilizing a superregenerative system with a common receiving and transmitting tube.

Referring now more particularly to the control unit 60, the latter comprises a limiter 61, the input circuit of which is connected to the diode load resistor 20 and the output circuit of which is connected to a diode rectifier 64 through a differentiating circuit 62, a clipper 69, an amplifier 63, and a blocking condenser 65. A resistor 66, which is by-passed for alternating currents by a condenser 68, is connected between the anode of tube 64 and ground and a resistor 67 is connected between the cathode and ground. The units 61-63, inclusive, and 69, comprising the limiter, the differentiating circuit, the clipper, and the amplifier may comprise suitable units that are well known in the art, and, hence, a detailed description is not required. The input circuit of quench amplifier 41 is connected to the anode of diode 64, while the input circuit of amplifier 57 is connected to the cathode of diode 64.

Coming now to the operation of the entire system in conjunction with the control unit 60, it will be seen that the derived pulse R is applied to the input circuit of control unit 60. A predetermined time interval after the application of pulse R to the input circuit of the unit 60, the transmitter portion of the system is keyed by the signal derived by rectifier 64 and transmits a signal of comparatively long duration. This signal is also picked up by the receiver and rectified to develop a pulse signal RT for application with the signal R to control unit 60. Limiter 61 derives a pair of time-spaced pulse signals of wave form R and RT and applies them to the differentiating circuit 62. Limiter 61 is designed so that it clips the peak of the exceedingly strong pulse RT but translates the comparatively weak signal R without alteration in wave form, even though the latter signal varies in amplitude over a wide range. The parameters of the differentiating circuit 62 are so selected that only the signal which has a steep wave front is effectively translated, the output signal being as indicated. This output signal is applied to the clipper 69 which responds only to signals of one polarity and translates a signal, as indicated, to unit 63. After amplification in unit 63, which also removes residual traces of the transmitted pulse, the signal is applied to amplifier 57 and also to rectifier 64. The latter derives a negative unidirectional potential for application through re-

sistor 43 to the control electrode of quench amplifier 41.

Control unit 60 is so designed that it is responsive to the field intensity of a wave signal received during a receiving interval at the receiver for deriving a control effect having a duration at least coextensive with the next succeeding interval during which a reply signal is transmitted. Preferably this control effect is also coextensive with the next succeeding receiving interval. Specifically, a unidirectional control potential is developed in the output circuit thereof, which is proportional to the field intensity of a received signal. This control effect is applied to the control electrode of quench amplifier tube 41, which operates as a class A amplifier, in the form of a negative bias of variable magnitude to control the gain of that stage. For a received signal of high field intensity, a relatively large negative bias is developed to reduce the gain of amplifier tube 41. This reduces the magnitude of the alternating potential developed in the output circuit of the amplifier tube 41 and, hence, reduces the alternating potential supplied through condenser 56 to the circuit 10 of the receiver, thereby reducing the receiver sensitivity inversely in accordance with the field intensity of the received signal.

When the gain of quench amplifier 41 is reduced, the alternating voltage applied to rectifier 50 is also reduced, thereby diminishing the magnitude of the derived unidirectional potential which is applied to the anode of amplifier 54. The pulse T that is developed by system 58 when it is keyed by a received signal is, therefore, translated by amplifier 54 at a reduced amplitude to the step-up transformer 17 and to the radio-frequency oscillator circuit 10, the oscillations of which are controlled by this pulse of reduced amplitude. Consequently, the field intensity of the transmitted signal which is radiated by antenna 22 is controlled inversely in accordance with the field intensity of the received signal. It will be seen, therefore, that the control action is effective to control both the field intensity of the transmitter and the sensitivity of the receiver inversely in accordance with the field intensity of the signal received by antenna 22 from a source. Conversely, when a signal of reduced field intensity is received, the gain of quench amplifier tube 41 is increased, thereby increasing the receiver sensitivity accordingly and also increasing the field intensity of the signal which is radiated by the transmitter.

It will be apparent from the circuit of Fig. 1 that the quench-oscillator system including the quench amplifier 41 and the rectifier 50 comprises the sole source of anode potential for amplifier 54, which amplifier, in response to a weak signal received by the antenna 22, requires a high anode potential to develop a strong output signal. Consequently, at such a time, a source of potential is required which is considerably higher than is needed for the anode of the other tubes, and the quench oscillator system is capable of meeting this peak-potential requirement.

While the arrangement of Fig. 1 discloses a super-regenerative system using a common receiving and transmitting tube, it will be manifest to one skilled in the art that the system can be modified in various ways, for example, to include separate transmitting and receiving tubes operating at the same or different frequencies and in circuit with separate antennas.

While applicant does not wish to be limited to

any particular circuit values for the embodiment of the invention described in connection with Fig. 1, the following set of representative values for the more critical elements are believed to be suitable in this circuit:

Tube 11	Type 2C22
Tube 19	Type 9004
Tubes 50 and 64	Type 6H6
Tube 41	Type 6V6
Tube 54	Type 807
Resistor 20	10,000 ohms
Resistors 43 and 66	0.22 megohm
Resistor 46	220 ohms
Resistor 55	22,000 ohms
Resistor 67	100,000 ohms
Condenser 13	1 to 3 micromicro-farads
Condenser 18	5 micromicrofarads
Condensers 47 and 68	0.01 microfarad
Condenser 65	0.001 microfarad
Condenser 59	0.05 microfarad
Inductance 12	0.15 microhenry
Step-up transformer 17	Ratio: 1 to 2.8
+B	+300 volts
+Sc	+100 volts
-C	-75 volts
Duration of received signal R	1 microsecond
Duration of transmitter signal T	10 microseconds
Frequency of oscillator 10	200 megacycles
Frequency of quench oscillator 40	200 kilocycles

Referring now to Fig. 2, there is shown in block form a modified system, in accordance with the invention, for receiving wave signals from a source and translating related wave signals thereto. This system comprises a receiver 10 of the superheterodyne type and a separate transmitter 12 which are interconnected through a control unit 13 which may be similar to the unit 60 of Fig. 1. Transmitter 12 has an antenna system 18, 19 and also is connected in circuit with the output circuit of a detector 77 in receiver 10. The superheterodyne receiver comprises, in the order named, an antenna system 11, 11, a radio-frequency amplifier 74, a frequency changer 75, an intermediate-frequency amplifier 76, and the detector 77. Control unit 13 is connected to the detector 77 and also to one or more stages of radio-frequency amplifier 74, frequency changer 75, and intermediate-frequency amplifier 76 for applying a control potential to these stages. The stages 74-77, inclusive, of the receiver and the transmitter 12 may be of well-known construction so that detailed illustration and description thereof are deemed unnecessary.

Referring briefly, however, to the operation of the system just described, wave signals are intercepted by the antenna 11, 11, are selected and amplified in radio-frequency amplifier 74, and are applied to frequency changer 75 where they are converted into intermediate-frequency signals which, in turn, are amplified in intermediate-frequency amplifier 76, and delivered to detector 77. Modulation components of the signals are derived in detector 77 and are applied to the control unit 13 where a control effect is derived which is proportional to the field intensity at the receiver of a received signal. This control effect, when applied to one or more of units 74-76, inclusive, regulates the sensitivity of the receiver inversely in accordance with the field intensity of the received signals. The same control potential,

being applied to the transmitter 12, is utilized to control the field intensity of the radiated signal which is developed when the transmitter is keyed into operation. The control potential may, for example, be applied to a control element in the modulator circuit of the transmitter. Modulation components derived by detector 77 are also supplied to conventional circuits in the transmitter 12 to trigger it into operation in response to each detected signal or to predetermined ones thereof.

In summary, therefore, the superheterodyne receiver 10 comprises means at a point for receiving wave signals from a source (not shown), and the transmitter 12 comprises means for transmitting related wave signals back to the source. Control unit 13 comprises means responsive to the field intensity of the received wave signal at the above-mentioned point for deriving a control effect, while conventional circuits of the transmitter 12 comprise means responsive to the control effect for controlling the field intensity, at the above-mentioned point, of the related transmitted signals inversely in accordance with the field intensity of the received signal. One or more stages of units 14, 15 and 16 comprise means responsive to the control effect developed in unit 13 to control the sensitivity of the means for receiving wave signals inversely in accordance with the field intensity of the wave signal received by the antenna system 11, 11.

As used in the instant specification, the term "related wave signal" is employed broadly to denote any type of signal which is transmitted by a responding unit of a two-way communication system in response to a wave signal which is received from a source. This language is intended to include a wave signal which is amplitude-, phase-, or frequency-modulated, a reflected wave signal, an unmodulated carrier-wave signal, or a supersonic wave signal.

While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A radio receiver-transmitter system comprising: means at a point for receiving from a remote radio transmitting station during spaced receiving intervals radio signals having a field intensity at said point which may vary and for transmitting during intervals intervening said receiving intervals reply radio signals; means responsive to the field intensity of a radio signal received during a receiving interval for deriving a control effect having a duration coextensive with the next succeeding interval during which a reply radio signal is transmitted; and a control system responsive to said control effect for controlling the field intensity at said point of said reply radio signal, transmitted during said next succeeding intervening interval, inversely in accordance with the field intensity of said radio signal received during said receiving interval.

2. A radio receiver-transmitter system comprising: means at a point for receiving from a remote radio transmitting station during spaced receiving intervals radio signals having a field intensity at said point which may vary and for transmitting during intervals intervening said re-

ceiving intervals reply radio signals; means responsive to the field intensity of a radio signal received during a receiving interval for deriving a control effect having a duration coextensive with at least the next succeeding receiving interval and including an intervening transmission interval; and a control system responsive to said control effect for controlling the sensitivity of said first-mentioned means during said next succeeding receiving interval and for controlling the field intensity at said point of said reply radio signal, transmitted during said intervening transmission interval inversely in accordance with the field intensity of said radio signal received during said receiving interval.

3. A radio receiver-transmitter system comprising: means at a point for receiving from a remote radio transmitting station during spaced receiving intervals pulse-modulated radio signals having a field intensity at said point which may vary and for transmitting during intervals intervening said receiving intervals pulse-modulated reply radio signals; means responsive to the field intensity of a pulse-modulated radio signal received during a receiving interval for deriving a control effect having a duration coextensive with the next succeeding interval during which a pulse-modulated radio signal is transmitted; and a control system responsive to said control effect for controlling the field intensity at said point of said pulse-modulated radio signal, transmitted during said next succeeding intervening interval, inversely in accordance with the field intensity of said pulse-modulated signal received during said receiving interval.

4. A radio receiver-transmitter system comprising: means at a point for receiving from a remote radio transmitting station during spaced receiving intervals radio signals having a field intensity at said point which may vary and for transmitting during intervals intervening and receiving intervals reply radio signals; means responsive to the field intensity of a radio signal during a receiving interval for deriving a control effect having a duration coextensive with the next succeeding interval during which a reply radio signal is transmitted; and a control system responsive to said control effect for so controlling the energization of said first-mentioned means during said next-succeeding interval that the field intensity at said point of said reply radio signal, transmitted during said next succeeding interval, varies inversely in accordance with the field intensity of said radio signal received during said receiving interval.

5. A radio receiver-transmitter system comprising: means at a point for receiving from a remote radio transmitting station during spaced receiving intervals radio signals having a field intensity at said point which may vary and for transmitting during intervals intervening said receiving intervals reply radio signals; means responsive to said received radio signals for developing auxiliary signals, means for utilizing said auxiliary signals to modulate said first-mentioned

means during said intervening intervals to produce said reply radio signals, means responsive to the field intensity of a radio signal received during a receiving interval for deriving a control effect having a duration coextending with the next succeeding interval during which a reply radio signal is transmitted; and a control system responsive to said control effect and coupled to said utilizing means for controlling the field intensity at said point of said reply radio signal, transmitted during said next succeeding intervening interval, inversely in accordance with the field intensity of said radio signal received during said receiving interval.

15. A wave-signal translating system comprising: regenerative means at a point for receiving wave signals from a remote source and for transmitting related wave signals in reply thereto; means responsive to the field intensity of received wave signals at said point for deriving a control effect; and a control system responsive to said control effect and including quench-oscillator means for controlling regeneration in said regenerative means during receiving intervals to provide gain-controlled superregenerative reception and for controlling the field intensity at said point of said related transmitted wave signals developed in said regenerative means during transmission intervals inversely in accordance with the field intensity of said received wave signals at said point.

20. A wave-signal translating system comprising: regenerative means at a point for receiving wave signals from a remote source and for transmitting related signals in reply thereto; means responsive to the field intensity of received wave signals at said point for deriving a control effect; and a control system responsive to said control effect and including quench-oscillator means for controlling regeneration in said regenerative means during receiving intervals to provide gain-controlled superregenerative reception and for controlling the field intensity at said point of said related transmitted wave signals developed in said regenerative means during transmission intervals and the sensitivity of said regenerative means during said receiving intervals for said received wave signals inversely in accordance with the field intensity of said received wave signals at said point.
